ATTORNEY

UNITED STATES PATENT OFFICE.

MARTIN EGNER, OF CLEVELAND, OHIO.

MUFFLER.

Application filed November 10, 1923. Serial No. 674,065.

My invention relates to mufflers and similar devices such as are used in connection with exhaust or similar systems.

The main object of my invention is a simple and efficient muffler means adapted to mitigate the noise of exhaust or similar systems without causing undue back pressure in the system and to be automatically cleaned by the exhaust or other fluid pressure passing therethrough. Other objects will appear during the description of the apparatus shown in the accompanying drawing.

My invention is sufficiently illustrated in the accompanying drawing in which Fig. 1 is a general perspective view of a muffler, partly in section to show the interior arrangement of elements, well adapted for the exhaust of an internal combustion engine and embodying the features of my invention; Fig. 2 is a general perspective view of a similar muffler, partly in section, showing one manner of attaching my invention to an existing muffler.

Similar reference characters refer to similar parts throughout the views.

In order to mitigate or eliminate the noise usually found in exhaust or similar systems, as in the exhaust of an internal combustion engine for instance, it is necessary that a muffling means of some kind is provided; such means however must not cause undue back pressure in the system.

Such a muffler means is shown in the accompanying drawing and comprises the shell A, the inlet member B, the outlet member C, and the partitions D and E.

The shell A is lined with asbestos or other heat insulating and sound absorbing material 10.

40 The inlet member B is also lined with similar material 11, is secured to one end of the shell A, and is provided with the inlet opening 12. It is observed that the bottom of this opening is substantially flush with the bottom of the inside of the shell; the purpose whereof will appear presently.

The outlet member C, also lined with similar material 13, in the present instance is made in the form of an inclined funnel comprising the inclined conical member 14 and the inclined conical member 15 having the outlet opening 16 flattened at the outer end to provide the inclined wall 17. It is to be

observed that the bottom of the opening 16 is also substantially flush with the bottom 55 of the inside of the shell; the purpose whereof will appear presently.

The partition D is located some distance from the inlet member and is provided with the release apertures 18 over the entire surface thereof and also with the clear passage opening 19 at the bottom and substantially 60 in alignment with the openings 12 and 16; the purpose whereof will appear presently.

The partition E is located next to the partition D, between the outlet member C and the partition D, and is provided with a group of release apertures 20 over the upper part thereof and also with the clear passage opening 21 at the bottom substantially 70 in alignment with the openings 12 and 16 and 19; the purpose whereof will appear presently.

The several members may be secured to each other by any suitable means or in any 75 suitable manner; the joints shown in the drawing give good results and the beaded joint between the shell A and outlet member C affords a ready means of joining these two members to complete the muffler after 80 each of these elements have been made up as units.

When this muffler is in operation, exhaust or other fluid pressure enters the muffler through the opening 12 and travels into the 85 compartment 22 where it can expand; then travels through the apertures 18 into the compartment 23 and thereby releases the fluid pressure from the compartment 22; then travels through the apertures 20 into 90 the compartment 24 and thereby releases the fluid pressure from the compartment 23. When this fluid pressure leaves the apertures 20, it is given a straight direction as indicated by the single dotted line 25 and 95 impinges on the conical and inclined surface 26 of the member C, is then directed downward in the general direction of the flow of the exhaust and impinges on the surface 27 of the member 15, is then directed upwardly 100 and again in the general direction of the flow of the exhaust and impinges on the surface 28 of the member 15, whereupon it flows out easily and freely through the outer end 105 of the opening 16. The partition D offers a certain amount of resistance to the fluid

pressure and prevents the same from rushing into the compartment 23 with full force and the partition E offers additional resistance to the fluid pressure and directs the same toward the surface 26.

It has previously been stated that the openings 12, 16, 19, and 21 are all in alignment with each other. The purpose thereof is to automatically clean the inside of the muffler. When fluid pressure enters the muffler through the opening 12, the force thereof directs it against the partition D at the bottom and some of this fluid pressure travels through the opening 19 with practically undiminished force, then travels through the opening 21 and out through the end at the opening 16 as indicated by the single dotted line 29. Therefore, a portion of this fluid pressure has a free passage way straight through the muffler at the bottom thereof and will automatically clean or blow out whatever sediment may collect there.

Under ordinary conditions, the muffler shown and described works very well with the two partitions; it is obvious however that more or less than two partitions may be used. It is not necessary that both of the partitions shown are provided in all cases; it is quite sufficient in many cases that some sort of a baffle means, either square across the muffler as shown or inclined, is provided to direct the fluid pressure longitudinally against the inclined face 26 and then out through the opening 16 as previously stated.

The spout 15 may also be eliminated in some cases since the impingement offered thereby is comparatively small.

A muffler of the character described may also be constructed for attachment to an existing muffler as is illustrated in Fig. 2 where the head B of Fig. 1 is eliminated and the end 30 of the shell A extends over the end 31 of the existing muffler F. In this instance, I prefer to slit the end 30 and employ the clamp G to firmly secure the end 30 to the end of the muffler F by means of the screw 32. In order to prevent longitudinal separation of the new and the existing mufflers, I also provide the screw 33 extending through both mufflers as shown.

It is observed that the present invention, among other features, directs the exhaust against one or more inclined walls where it is deflected and thereby, in addition to the other baffle means, reduces the force and consequently the noise of the exhaust. The lining on the inside of the muffler also helps to eliminate the noise. The main feature, however, is to provide a deflector means near the discharge end of the muffler to angularly deflect the exhaust in a general direction toward the outlet and not deflect it against the general direction of its travel.

I may make modifications other than those pointed out within the scope of the appended

claims. Therefore, without limiting myself to the precise construction shown and described and otherwise disclosed, I claim:

1. An exhaust muffling device, including, a shell having an exhaust inlet opening near the bottom of one end thereof, a funnel shaped outlet means on the other end of said shell and sloping downwardly to form an inclined baffle for some of the exhaust in the general direction of the flow of the exhaust and having an outlet opening in the outer end thereof in alignment with said inlet opening, and a straight and unobstructed passage way between said openings along the bottom of the inside of said shell to permit some of the exhaust to flow unrestrictedly through the passage way and thereby automatically remove foreign substance from the bottom of the inside of said shell.

2. An exhaust muffling device, including, a shell having an inclined outlet member provided with an outlet opening having the lower edge thereof flush with the inside of said shell, baffling means in said shell and provided with openings in alignment with said outlet opening, an inlet means having an inlet opening in alignment with said outlet opening and with said openings in the baffling means to form a straight passage way through the muffler device and thereby permit some of the exhaust to flow through the passage way along the bottom of the inside of the shell to remove foreign substance therefrom, and said baffling means arranged to offer no restriction to the flow of exhaust through the passage way.

3. An exhaust muffler device, including, a shell having a head at each end thereof, one of said heads having an inlet means, the other of said heads having an outlet means, a partition in said shell adjacent to and spaced from the head with the inlet means and provided with apertures staggered over the entire surface thereof, a partition in said shell adjacent to and spaced from the head with the outlet means and provided with apertures over a sectoral portion of the surface thereof, the sectoral portion being out of alignment with the outlet means, and the combined area of the apertures in the first mentioned partition being greater than the combined area of the apertures in the second-mentioned partition.

4. An exhaust muffling device, including, a shell, an inlet means on one end of said shell at the bottom of said device, an inclined funnel shaped outlet member on the other end of said shell and the spout thereof located at the bottom of said device, a partition in said shell adjacent to and spaced from said inlet means and provided with release apertures over the entire surface thereof, and a second partition in said shell adjacent to and spaced from said outlet member and provided with a group of re-

lease apertures over the upper portion of the surface thereof.

5. An exhaust muffling device, including, a shell, an inlet means on one end of said shell and the opening thereof located at the bottom of said device, an inclined funnel shaped outlet member on the other end of said shell and the opening in the spout thereof located at the bottom of said device 10 in alignment with the opening in said inlet means; a partition in said shell adjacent to and spaced from said inlet means and provided with release apertures over the entire surface thereof and with a clear passage 15 aperture near the bottom thereof, said clear passage aperture in alignment with the openings in said inlet means and the opening in said spout, and a second partition in said shell adjacent to and spaced from said 20 outlet member and provided with a group of release apertures over the upper surface thereof and with a clear passage opening at the bottom thereof in alignment with the opening in said inlet means and with the 25 opening in said spout and with said clear passage aperture of the first mentioned partition.

6. An exhaust muffling device, including, a shell having an inlet means on one end thereof, a downwardly inclined funnel

shaped outlet means on the other end of said shell, a partition in said shell inward of said inlet means to form a compartment adjacent to the inlet end of said shell to permit the exhaust to expand therein, a ²⁵ partition in said shell inward of the first mentioned partition to form a second compartment between both of the partitions to permit the exhaust to further expand therein and to form a third compartment between ⁴⁰ the last mentioned partition and said outlet means to permit the exhaust to further expand therein, the first mentioned partition provided with apertures over the entire surface thereof to permit the exhaust to ⁴⁵ flow into the second compartment from any position in the first compartment and without changing the direction of the flow thereof, the second mentioned partition provided with apertures over the upper surface thereof to direct the flow of the exhaust upwardly and to permit the exhaust to flow into the third compartment and to confine the flow thereof to the top of the device and to direct the same against the inclined outlet ⁵⁰ ⁵⁵ means.

In testimony whereof I hereunto affix my signature:

MARTIN EGNER.
